UNITED STATES PATENT OFFICE.

SOLOMON H. GOLDBERG, OF CHICAGO, ILLINOIS.

RESILIENT SUPPORT FOR PACKING FRAGILE ARTICLES.

Application filed May 1, 1924. Serial No. 710,300.

To all whom it may concern:

Be it known that I, SOLOMON H. GOLDBERG, a citizen of the United States, residing in the city of Chicago, county of Cook, and State of Illinois, have invented certain new and useful Improvements in Resilient Supports for Packing Fragile Articles, of which the following is a specification.

This invention relates to improvements in resilient support for packing fragile articles, and refers more particularly to a construction especially adapted for use in the shipping of fragile articles, which are easily broken, to reduce to an absolute minimum the amount of breakage usually incident to shipping.

In the preferred embodiment of my invention, it is particularly adapted for use in shipping radio sets. During the past few years, countless methods of packing have been utilized, in the shipping of these radio sets, but these various methods of packing were all defective, resulting in a high breakage.

The express companies handling the shipping of these sets have disbursed hundreds of thousands of dollars as a result of the breakage in transit of such a delicate and fragile article as a radio set.

I have evolved a construction consisting of a resilient metallic support to be positioned in a shipping crate or box, on which the radio set or analogous fragile constructions are placed.

In the drawings:

Fig. 1 is a perspective view of shipping crate, resilient support and radio set in place.

Fig. 2 is a plan view of the supports with the radio set shown in dotted lines.

Fig. 3 is a perspective view of the support, illustrating one form of construction.

Fig. 4 is a detail view, with parts broken away, illustrating the spring connection of both ends of the support.

Referring to the drawings, 1 designates a shipping crate or box, of wood, fibre or other suitable material having the bottom 2, sides and ends 3 and cover portions 4. Removably supported on the bottom 2 are the resilient supports 5, which may be of wire or other material having analogous resilient qualities. The support 5 has laterally extending portions 6, adapted to rest on the bottom of the box; U-shaped return bent portions 7, which may incline upwardly as shown at 8 and cross connecting bars 9. The

support is preferably formed from a single length of wire, one end 10 having more or less fixedly attached thereto the coil spring 11, into which the opposite end 12 is adapted to be inserted. One of the advantages of this particular form of spring connection is the ease of assembly and disassembly, and the certainty of the connection in use.

I have shown in Figs. 1 and 2, two supports 5 having their inner return bent portions 7 overlapping. This is one of the preferred forms of construction, but I wish to point out that one elongated support of this general character may be employed or more than two may be used. As shown in Fig. 2, the inner cross connecting pieces 9, provide a support for the radio set designated as 13, at the point of highest strain.

It will be seen that I have provided a readily adjustable support of this character, for use particularly in the shipment of radio sets, by which the shaking and vibrating action encountered in shipment is taken up by the resiliency of the supports, which, in effect, perform the function of springs. In addition, the delicate fittings and accessories positioned in the box are prevented from breaking due to the spring action of these resilient supports and the consequent ready adjustment to the exigencies of shipping. In other words, these delicate fittings and accessories are more or less fixedly attached to the box 13 and a sudden jar will snap them off, on account of the lack of resiliency. It will be readily seen that with the advantages of my resilient construction, this objection will be overcome.

The supports are, of course, adjustable laterally to accommodate articles of various lengths. As pointed out, the return bends 7 may incline upwardly as shown at 8 or they may lie in the same horizontal plane as the base portions 6.

I have specifically described the particular embodiment of my invention as applied to a radio set. The same advantages can be attained when shipping other similar fragile or easily breakable constructions.

I claim as my invention:

1. A construction of the character described, consisting of a box having a base portion, a flexible support mounted therein, comprising a single piece of wire bent to form substantially parallel base supports, having return bent ends integrally connected with cross pieces.

2. A construction of the character described, consisting of a box having a base portion, a flexible support mounted therein, comprising a single piece of wire bent to form substantially parallel base supports, having return bent ends upwardly inclined integrally connected with cross pieces. 30
3. A construction of the character described, consisting of a box having a base portion, a flexible support mounted therein, comprising a single piece of wire bent to form substantially parallel base supports, having return bent ends upwardly inclined and inwardly extending, integrally connected with cross pieces. 35
4. A construction of the character described, consisting of a box having a base portion, resilient metallic supports mounted in said box, comprising laterally extending base portions having return bent ends upwardly inclined integrally connected with transverse cross pieces, the inner cross piece of adjacent supports overlapping to provide maximum strength. 40
5. A resilient support comprising a single piece of wire bent to form laterally extending base portions having return bends inclined upwardly, and integral cross members connecting the return bends, the ends of wire being held together under spring tension. 45
6. A resilient support comprising a single piece of wire bent to form laterally extending parallel base portions having return bends inclined upwardly and inwardly, and integral cross members connecting the return bends. 50
7. A resilient support comprising a single piece of wire bent to form laterally extending base portions having return bends inclined upwardly, and integral cross members connecting the return bends, the ends of wire being held together under spring tension. 55
8. Resilient supports adapted for use with radio sets, comprising resilient wire bent to form laterally extending supporting base portions terminating in return bends upwardly and inwardly inclined, and integral cross pieces connecting the return bends, the cross pieces of adjacent cross pieces being adapted to overlap when adapted to overlap when in position. 60
9. Resilient supports adapted for use with radio sets, comprising resilient wire bent to form laterally extending substantially parallel supporting base portions terminating in return bends upwardly and inwardly inclined, and integral cross pieces connecting the return bends, the cross pieces of adjacent cross pieces being adapted to overlap when in position. 65

SOLOMON H. GOLDBERG.
